Attorney.

UNITED STATES PATENT OFFICE.

WILLIAM THOMAS SHEA, OF CHICAGO, ILLINOIS.

BOOK-SUPPORT.

No. 831,193.

Specification of Letters Patent.

Patented Sept. 18, 1906.

Application filed February 26, 1906. Serial No. 302,884.

To all whom it may concern:

Be it known that I, WILLIAM THOMAS SHEA, a citizen of the United States, residing in the city of Chicago, in the county of Cook and State of Illinois, have invented new and useful Improvements in Book-Supports, of which the following is a complete and comprehensive exposition and specification, being such as will enable others familiar with the art to which it appertains to make and use the same with absolute exactitude.

My present invention relates to book-supports in which my object, broadly speaking, is to provide a construction of the class stated which will be neat and attractive in appearance, strong and durable in construction, simple in operation, and which may be manufactured and sold at a very low price.

More particularly, my object is to provide a construction for holding books or the like in a readily-accessible position whereby the leaves of the book may be turned without appreciable effort and at the same time being so positioned as to bring the matter thereon into the most natural and easy positions of the observer and all without the necessity of moving or lifting the book.

From the above it will be readily apparent that my invention is intended more especially for large volumes—such, for instance, as books for displaying samples attached to its leaves, for atlases, and the like—which are not easily handled, and especially where it is desired that the book remain open and in a position to readily display the matter thereon contained, and it may also be used for holding smaller books with great success, and especially books of reference.

Other objects and particular advantages of my invention will present themselves in the course of the ensuing specification.

The preferred embodiment of my invention is shown most clearly in the accompanying drawings, forming part of this specification, in which—

Figure 1 is a front elevation of my invention as supporting a book in the desired position, the device being shown as resting on a level surface—as, for instance, a table or the like. Fig. 2 shows a slightly-modified construction, whereby the invention is particularly adapted for hanging upon a wall or the like. Fig. 3 is a central vertical section of the invention as suspended upon a wall or the like. Fig. 4 is a top plan view of the inven-

tion. Fig. 5 is an enlarged detail plan of the upper face of the central aperture in the shelf, and Fig 6 is a detail view showing a vertical section taken through said central aperture.

Similar indices denote like parts throughout the several views of the drawings.

In order that my invention and its application may be fully understood and its several advantages be fully appreciated, I will now take up a detail description thereof and will describe the several parts and the operation thereof as briefly and as compactly as I may.

For the purpose of making clear the application of my invention I have shown a book in connection therewith, of which the letter A denotes the leaves, B and B' the two sides, and C the back of the book.

In the invention proper the numeral 1 denotes a shelf of rectangular shape and adapted in each instance to be retained practically level or slanting slightly forward, as desired. Formed through the center, longitudinally of the shelf 1 and slightly forward of one edge thereof, is the deltoid or triangular aperture 2. (Shown most clearly in Figs. 5 and 6.) The angular sides of said aperture 2 diverge from the top downward, as is indicated, thereby forming a tapering aperture, substantially as shown. The numeral 3 denotes the standard, it being triangular in cross-section, and its lower end portion is formed flaring, producing the head portion 3' integral therewith. From the above it will be apparent that the upper end of the standard may be inserted from below the shelf through said aperture 2, passing the standard upward therethrough until the flaring portion of the standard engages with the diverging sides of the aperture 2, whereby the standard will be prevented from passing farther, and by reason of the peculiar inclination given to the sides of said aperture 2 it will be seen that the standard is thereby caused to incline rearward, whereby the back of the upper end of the standard is caused to be on a line vertically with the rear edge of the shelf, as is indicated in Fig. 3. In the upper central portion of the standard 3 is formed an aperture 3'', whereby the device may be suspended from a nail or the like, which is denoted by the letter D in Figs. 2 and 3.

As shown in Fig. 1, the head 3' below the shelf 1 is dispensed with, whereby the bottom of the shelf may rest flat on a table or the

like, as represented by the line E, in which position the upper rear edge of the standard will be directly above the rear edge of the shelf, which of course gives a rearwardly inclination to the standard, which is essential to practical success of this invention.

It will now be understood that the book above referred to may be placed on the standard by allowing the standard to be inserted 10 upward between the body of the book and the back C, as shown in Fig. 3, and allowing the lower edges of the sides B and B' to rest on the shelf 1. The book will then be supported as shown in Fig. 1, inclining rearward, as 15 shown in Fig. 3, and where it will be perfectly balanced, allowing the leaves to be turned without interfering with the shelf and by reason of the inclination retaining the book open at the pages left. It will also be noticed 20 that not only being adapted to rest on a table or the like the device containing the book may be lifted and suspended from a nail or the like on the wall H, passing the nail-head through the aperture 3" and allowing the rear 25 edge of the shelf to contact with the wall, as shown in Fig. 3.

Where it is intended that the device be suspended from the wall only, I have found it desirable to allow the standard 3 to project 30 through below the lower face of the shelf, forming the flaring head 3', having an aperture therethrough, in which may be placed a pin 4 or the like to extend out to form a convenient place from which to suspend some accessory article—as, for instance, a tablet or a pencil. It will be noticed also that, if desired, the pin 4 may extend back into the wall H, as 35 shown in Fig. 3, which will prevent the device from swinging sidewise. Under certain 40 conditions I have also found it advantageous to employ the two arms 5 and 6 for the sides B and B', respectively, to rest against, as indicated in Fig. 2. Said arms are simply strips having each an aperture in their upper 45 ends to engage over the nail D or the like, crossing each other in the rear of the upper end of the standard 3 and their lower portions resting loosely in the open slots, which slots extend inward from the ends and are located near the rear edge of the shelf 1, as 50 shown in Fig. 4. Said arms 5 and 6 should extend below the shelf 1 and may have the pins 7 and 8, respectively, extending out

therefrom for the same purposes as the said pin 4.

55

From the above description and showing it is most notably apparent that I have accomplished the objects of my invention, and the device may be employed in a number of ways, as a particular instance of which I might mention that the book may contain samples of cloth secured on its pages, as usually employed by merchant-tailors. Heretofore it has been customary for such books to lay flat and closed when not in use, thereby occupying an unnecessary amount of space and being difficult to handle and display; but by the employment of my invention it is apparent that the book will occupy but a minimum of space, either on a table or when suspended on a wall, and in either instance it may be left open for displaying the samples to the best advantage, and one has only to turn the leaves without otherwise handling the book.

70

What I claim, and desire to secure by Letters Patent of the United States, is—

75

1. A book-support comprising a shelf having a central aperture and a standard adapted to pass between the body and back of a book, the standard being removably secured in an 80 inclined position in the aperture in the shelf, its upper end being in the vertical plane of the rear edge of the shelf and having a perforation, as and for the purposes set forth.

85

2. A book-support comprising a shelf having a central aperture and slotted at each end, a standard adapted to pass between the body and back of a book, the standard being removably secured in an inclined position in the aperture in the shelf, its upper end being 90 in the vertical plane of the rear edge of the shelf and having a perforation, and arms in engagement near their lower ends with the slots in the shelf and perforated and crossed at their upper ends, the perforations in the 95 arms registering with the perforation in the standard, substantially as described and for the purposes set forth.

95

In testimony whereof I have hereunto signed this specification in the presence of 100 two subscribing witnesses.

WILLIAM THOMAS SHEA.
